ADELARD F. MARTEL, OF BURLINGAME, CALIFORNIA.

AUTOMATIC CONTROLLING DEVICE FOR PUMPING PLANTS.

1,252,343.

Specification of Letters Patent. Patented Jan. 1, 1918.

Application filed July 29, 1913. Serial No. 781,813.

To all whom it may concern:

Be it known that I, ALFRED F. GROHNERT, residing in the city of Burlingame, county of San Mateo, State of California, have invented certain new and useful Improvements 5 in Automatic Controlling Devices for Pumping Plants, whereof the following is a specification.

This invention relates to an "automatic 10 controlling device for pumping plant."

The principal object of this invention is to provide means for shutting off the source 15 of power from the pump, when the pump ceases to elevate or discharge water or any other liquid that it may be handling.

Another object is to give visible and audible warning when the pump ceases to discharge. Other objects and advantages will appear as the description of my invention 20 progresses.

In the single sheet of drawing accompanying this specification, I have illustrated my invention in what I consider its best form.

In the drawings:

25 Figure 1 is a diagrammatic side elevation of a pump-governor or power control connected therewith, and constructed in accordance with this invention. The control mechanism is in relatively exaggerated proportion, better to disclose its important features.

30 Fig. 2 is a fragmentary detail side elevation of a fuel pipe, having a cut-off valve therein arranged in operative relation with the control mechanism.

35 In detail the construction consists of the pump 1, of any desired form, preferably of centrifugal type having the suction inlet 2 and the discharge outlet 3. The pump is driven in this present case by an electric 40 motor 4 diagrammatically indicated in Fig. 1, such a motor and its mechanical connections being so well known that further description of same is unnecessary.

45 The discharge pipe 3 is provided with the by-pass or bleeder 5, discharging into the reservoir 6. This reservoir is provided with a central upright column 7, preferably a pipe 95 screwed into the fitting 8, attached to the

bottom of the reservoir. The liquid discharged into the reservoir flows out through 50 the ports 9, through the fitting 8, and the outlet 10, back into the well or elsewhere. The valve 11 is provided for regulating the rate of discharge from the reservoir. The overflow pipe 12 determines the maximum 55 level the liquid can attain in the reservoir.

The float 13 has a central tube 14 extending therethrough, and upward, and is telescoped over the column 7, by which it is guided. The superstructure 15 extending 60 above and across the reservoir has a central opening acting as a guide for the tube 14, inclosing the column 7.

Before starting the motor, which drives the pump, there is obviously no liquid in 65 the reservoir to support the float 13; it is therefore elevated and the latch 16 thereon engaged with the hook 17 attached to the superstructure 15.

In Fig. 1 the prime mover 4 is an electric 70 motor, the leads 18 and 19 of which are connected with the knife switch, comprising the usual double contact members 20, only one of which appears in the drawing because one is behind the other. These contacts are 75 mounted upon the insulating block 21, fixed to the superstructure 15. The circuit is closed through the knife switch by the blade 22, pivoted at 23 in a bracket fixed upon the insulating block 21. The contact end 24 80 of the blade passes between the contacts 20. The motor is started by manually closing this knife switch.

When the liquid discharges from the pump through the pipe 3, a small quantity is bypassed through pipe 5, to the reservoir, causing the float 13 to rise, automatically releasing the latch, which leaves the float free to descend as the water lowers in the reservoir. 90

The column 7 is provided with the annular chamber 25 suspended therefrom. The tube 14 is provided with the annular semaphore 26, adapted to disappear within the chamber 25 when the float is up. The tube 14 is 95 provided with the trip 27 fixed thereon.

This invention operates substantially as follows:

Presuming the pump to be operating properly, with the proper water level in the reservoir and the float 13 supported by its own buoyancy, so long as the pump continues to discharge, the control mechanism will remain normally inactive, the same quantity flowing into the reservoir being discharged through the bottom thereof. Just as soon as the pump fails to discharge the full amount of liquid the liquid in the reservoir will drain out through the pipe 10 lowering the trip 27, until it forces down the pivoted blade 22, pulling the end 24 out of engagement with the contacts 20 opening the circuit and stopping the motor.

The descent of the trip 27 also closes the alarm circuit comprising the contacts 28 and 29 mounted upon the insulated block 30, fixed to the superstructure. These contacts control the circuit flowing from the battery 31, through the vibrating bell 32, and through the contacts, back to the battery. The bell 32 may be located at any desirable distance from the controlling mechanism and may be duplicated as desired. The descent of the float, also exposes the semaphore 26 to view beneath the chamber 25. The semaphore is preferably painted in some distinguishing manner to attract observation. The location of the apparatus can be designated by a flag on the staff 33.

If a steam engine, internal combustion motor, or other form of prime mover is substituted for the motor 4, the valve mechanism illustrated in Fig. 2 will be substituted for the knife switch mechanism. The fuel pipe 34 is provided with the valve 35, having the control lever 36 arranged in operative relation with and adapted to be depressed by the trip 27 to shut off the source of energy to the prime mover.

Having thus described my invention, and believing I have produced useful and novel improvements in the art to which it appertains, let it be understood that I do not wish to be limited to the exact construction and arrangement of the several parts composing the same, as many changes can be made without departing from the spirit thereof, but what I claim and desire to secure by United States Letters Patent is:

1. In combination with a pump and an electric motor to operate the same, a switch for said electric motor, a controlling device for said switch comprising a tank provided with a central column, a float in said tank provided with a central tube slidably mounted on said column and a trip on said tube adapted to automatically open said switch and thereby stop the motor.

2. In combination with a pump provided

with a motor to operate the same and a signaling device, a combined controlling mechanism for said motor and signaling device consisting of a tank connected to said pump and provided with a central column, a switch on said tank for said motor and a second switch also on said tank for said signaling device, a cylindrical float in said tank provided with a central tube slidably mounted on said column and a trip on said tube adapted to open simultaneously said motor switch and close said signaling switch.

3. In combination with a pump, a motor and a signaling device, a controlling mechanism for said motor and signaling device, comprising a tank connected to said pump and provided with a superstructure, a vertically operating cylindrical float in said tank provided with a central tube passing through said superstructure and guided thereby, a pair of switches independently mounted on said superstructure and connected respectively to the motor and signaling device and means on said tube to operate said switches.

4. In an apparatus of the character described, a pump provided with a motor for operating the same, a controlling device for said motor consisting of a tank connected to said pump, a switch mounted on said tank and connected to said motor, a cylindrical float in said tank provided with a central tube, a flange on said tube adapted to open said switch and thereby stop said motor.

5. In combination with a pump and its operating motor, a controlling device for said motor comprising a tank connected to said pump and provided with a superstructure, a float in said tank provided with means adapted to engage said controlling device, a holding device for said float consisting of a hook secured to said superstructure and a latch about said float engaging said hook to thereby hold said float in non-operative position and means for automatically disengaging said float.

6. An apparatus of the character described comprising a centrifugal pump provided with a discharge pipe and an electric motor for operating said pump, a by-pass connected to said discharge pipe, a controlling mechanism for said motor consisting of a water receiving tank connected to said by-pass, a float in said tank, a semaphore connected to said float and means for operating said semaphore.

7. An apparatus of the character described comprising a centrifugal pump provided with an electric motor for operating the same and a discharge pipe, a by-pass connected to said discharge pipe, a controlling mechanism for said motor consisting

of a water receiving tank connected to said by-pass and means in said tank to regulate the rate of discharge therefrom and the maximum level of water therein, a float in said tank, a semaphore connected to said float and operated thereby.

In testimony that I claim the foregoing

I have hereto set my hand in the presence of witnesses, this twenty-first day of July, 1913.

ALFRED F. GROHNERT.
